Primary Examiner — Kelley A Donnelly(74) *Attorney, Agent, or Firm* — Tucker Ellis LLP(57) **CLAIM**

The ornamental design for a shelving unit, as shown and described.

DESCRIPTION

FIG. 1 is a front, right side, top perspective view of a shelving unit embodying my new design;

FIG. 2 is a rear, left side, bottom perspective view thereof;

FIG. 3 is a front view thereof;

FIG. 4 is a left side view thereof;

FIG. 5 is a top view thereof;

FIG. 6 is an enlarged detail of the area denoted by reference numeral 6 in FIG. 1;

FIG. 7 is a rear view of the shelving unit;

FIG. 8 is a bottom view thereof;

FIG. 9 is a right side view thereof; and,

FIG. 10 is enlarged detail of the area denoted by reference numeral 10 in FIG. 1.

The broken lines in the drawings represent an unclaimed boundary for denoting the areas of detail.
